SEWING MACHINE

Henry Weissmann, Stapleton, Staten Island, N. Y.

Application May 27, 1937, Serial No. 145,014

4 Claims. (Cl. 112—191)

This invention relates to new and useful improvements in the bobbin mechanism of a sewing machine.

The invention has for an object the construction of a bobbin mechanism which is characterized by a bobbin container for the thread, an annular gear around said container and rotatively supported at its edges for supporting the container, and a novel arrangement for permitting the top thread loop passing around the bobbin to interengage with the bobbin thread.

Another object of the invention is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a side elevational view of a machine constructed according to this invention.

Fig. 2 is a fragmentary enlarged elevational view looking in the direction of the line 2—2 of Fig. 1.

Fig. 3 is a sectional view taken on the line 3—3 of Fig. 2.

Fig. 4 is a side elevational view of the bobbin container per se, with the thread loop schematically applied.

Fig. 4a is a fragmentary horizontal sectional view taken on the line 4a of Fig. 4.

Fig. 5 is a sectional view taken on the line 5—5 of Fig. 2.

Fig. 6 is a sectional view of a bobbin container constructed according to another form of the invention.

Fig. 7 is a transverse sectional view similar to Fig. 3 but illustrating another form of the invention, a simplified form.

In Fig. 1 a standard sewing machine 10 is illustrated having the customary cast base plate 10a, the wheel drive 10b, the needle bar 10c, and the pressure foot 10d. The details of this sewing machine will not be given in this specification since they form no part of the invention.

The invention resides in the provision of a bobbin container 11 formed with a passage 11a for the thread. An annular gear 12 is mounted around the container and has the root 12a between a pair of adjacent gear teeth cut deep (see Figs. 2 and 4a). Top thread loop catch-

ing hooks 13 and 14 are mounted on the container 11 at the sides of the gear 12 to guide the loop of thread 14' into the cut 12a of the gear 12 (see Fig. 4). Three rotatively supported pinions 15a, 15b and 15c have flanges 15 engaging the sides of the gear for rotatively supporting the same. These flanges are formed with peripheral cuts 15' synchronized to align with the cut 12a in the gear 12 to pass said thread loop during the rotation of the gears. 10

The bobbin container 11 comprises a base portion 11b having a central projection 11c on which a bobbin 11d is rotatively supported. A cover 11e engages over the top of the base portion and is removably supported in position by 15 a peg 11f engaging into an opening in the projection 11c. The space 11a occurs between the peripheral edges of the body 11b and the cover 11e. The cover may be removed to replace the bobbin. 20

The annular gear 12 is attached to the top portion of the container body 11b. The thread catching hook 13 is soldered or brazed to the top face of the gear 12. The thread catching hook 14 is disposed immediately below and is 25 formed by a projecting end of a strip 14a which is soldered or brazed upon the container and extends in a helical band and constitutes a cam for the purpose hereinafter described.

The pinion gear 15a is rotatively supported in 30 a bracket 17 which is attached to the underside of the base 10a. The pinion 15b is supported on a bracket 18 similarly supported. The pinion 15c is supported on a bracket 19, also similarly supported. One of the pinion gears, the pinion 35 gear 15a, is driven and synchronized with the sewing machine. This pinion gear is mounted on a shaft 20 which is provided with a bevel gear 21 meshing with a gear 22 on a rotatively supported shaft 23 connected by gears 24 with 40 a shaft 25 extending upwards into the body of the sewing machine and connected with some rotating part thereof. The details of this connection are not shown on the drawings as they form no part of the invention. The connection 45 should be such that the bobbin container 11 is caused to rotate two complete revolutions for each cycle of the needle bar 10c.

Certain mechanism is provided for assisting 50 the top thread loop 14' to engage around the bobbin container 11. This mechanism includes the cam strip 14a which tends to guide the thread loop downwards over the bottom face of the bobbin container. This mechanism also includes an arm 28 which is pivotally supported 55

- at its outer end on a bracket 29 attached on the base 10a. A pintle 30 is used for the pivotal supporting. A spring 31 is coaxial on the pintle and acts between the bracket 29 and the arm 28 for normally urging the arm upwards. A member 32 is mounted on the arm 28 and extends under the cam 14a (see particularly Fig. 3) in a manner so as to pivot the arm downwards as the bobbin container turns. The free end 10 28' of the arm 28 is adapted to engage into the loop of the top thread as it is formed by the needle and to move the loop downwards (see Fig. 4) so as to help maintain the thread of the loop to extend along the cam strip 14a.
- 15 The cam strip 14a extends substantially one-half of the circumference of the bobbin container and then the member 32 drops off the end of the cam and is snapped upwards to its original position, indicated by the dot and dash lines 28a in Fig. 5. There is a small projection 33 on the body of the bobbin container 11 immediately above the end of the cam 14a to prevent the loop thread from slipping back over the bobbin container. The loop thread is now more than half way 20 around the container and as the gear 12 turns and the loop is drawn upwards it will finish its circling act.
- The machine base 10a is formed with openings 30 in its top face which are closed by conventional slides 34. It is also provided with a plate 35 for the feeders 36. This plate has an opening 37 for the needle 38 of the sewing machine to engage through. The feeders 36 are operated in the usual manner and so is the needle.
- 35 In Fig. 6 a modified form of bobbin container is disclosed which comprises a container 41 having a top cover 42 engaging into the top thereof. This cover has a central opening 43 through which the thread 44 from the bobbin 45 may pass. The 40 container 41 is provided with the gear 12. In other respects this bobbin container is identical to that previously shown and its position and operation are the same.
- The operation of the device is as follows:—
- 45 When the needle 38 reaches its lowermost position and then starts to travel upwards, the top thread in the needle is slightly looped. The loop catching hooks 13 and 14 catch this loop 14' and drop a portion of it into the deep cut root 12a 50 between a pair of the teeth of the gear 12. The bobbin container 11 is being turned by the drive which connects with the pinion gear 15a. The flanges 15 have niches 15' which are synchronized with the root 12a to permit the thread to 55 pass the flanges of each of the pinion gears as the bobbin container 11 turns. The lower portion of the thread loop 14' guides along the cam 14a and the loop 14' is also caught by the end of the arm 28 which moves it downwards at the same 60 rate as the pitch of the cam strip 14a so that the loop extends along the said cam strip 14a. This cam strip guides the loop to the bottom of the bobbin container and so the loop extends completely around the bobbin container and catches 65 the bobbin thread. The arm 28 is moved downwards by the member 32 engaging the cam 14a, and when the member 32 is dropped the arm 28 will move back to its original position and be ready for the next thread loop. This arm will 70 be moved downwards again when the bobbin container 11 reaches its initial position, since then the finger 32 will again engage beneath a portion of the cam strip 14a which will again move it downwards.
- 75 In Fig. 7 a simplified form of the invention has

been disclosed. This form is a preferred one. Essentially, it consists of a bobbin container 11' of comparatively shallow depth and formed with a passage 11a for the thread. An annular gear 12' is mounted around the container 11' and is 5 substantially of the same width as the depth of the container 11'. The gear 12' has one root between a pair of adjacent gear teeth cut deep, indicated by numeral 12a. This deep cut root 12a is synchronized with the cuts 15' on the 10 flanges 15 of the supporting gears which support the gear 12 in the identical manner previously described. These same parts are indicated in Fig. 7 by the same reference numerals used in the 15 prior disclosure.

Mounted on the gear 12' at the deep root cut location 12a there is a top hook 13. This hook is above a bottom hook 13a. This bottom hook 13a is substantially at the same position as the bottom face of the container 11'.

The container 11' is illustrated with a removable cover 11e and houses a bobbin 11dd. In other respects this form of the invention is identical to the previous form and the corresponding parts may be recognized by the same reference numerals, except for the fact that it lacks the cam strip 14a, the arm 28, and the other associated parts for guiding the thread around the container. This form of the invention does not need the guiding means since it is of a narrow enough width for the thread to engage around the container by itself.

The operation of this form of the device is as follows:—

The top thread which is carried down by the 35 needle 38 forms a loop 14' which is picked up simultaneously by the two hooks 13 and 13a. Then a portion of the loop falls into the root 12a. As the container 11' rotates the loop 14' will be drawn over the entire container 11' and catch 40 the thread of the bobbin.

While I have illustrated and described my invention with some degree of particularity, I realize that in practice various alterations therein may be made. I therefore reserve the right and 45 privilege of changing the form of the details of construction or otherwise altering the arrangement of the correlated parts without departing from the spirit or the scope of the appended claims.

Having thus described my invention, what I claim as new and desire to have secured by United States Letters Patent is:—

1. In a sewing machine, a bobbin container with a passage for the thread, an annular gear around 55 said container and having the root between a pair of adjacent gear teeth cut deep, top thread loop catching hooks mounted on said container at the sides of said gear to guide the loop into said cut of said gear, rotatively supported pinion gears 60 meshing with said gear and having flanges engaging the sides of said gear and rotatively supporting same, said flanges having peripheral cuts synchronized to align with said cut in said gear to pass said thread loop during rotation of said 65 gears.

2. In a sewing machine, a bobbin container with a passage for the thread, an annular gear around 70 said container and having the root between a pair of adjacent gear teeth cut deep, top thread loop catching hooks mounted on said container at the sides of said gear to guide the loop into said cut of said gear, rotatively supported pinion gears meshing with said gear and having flanges engaging the sides of said gear and rotatively sup- 75

porting same, said flanges having peripheral cuts synchronized to align with said cut in said gear to pass said thread loop during rotation of said gears, said container being much deeper than the depth of said gear, a spiral cam along the side of said container and connecting with one of said hooks for guiding the thread loop around said container. 5

3. In a sewing machine, a bobbin container with a passage for the thread, an annular gear around said container and having the root between a pair of adjacent gear teeth cut deep, top thread loop catching hooks mounted on said container at the sides of said gear to guide the loop into said cut of said gear, rotatively supported pinion gears meshing with said gear and having flanges engaging the sides of said gear and rotatively supporting same, said flanges having peripheral cuts synchronized to align with said cut in said gear to pass said thread loop during rotation of said gears, said container be-

ing much deeper than the depth of said gear, a spiral cam along the side of said container and connecting with one of said hooks for guiding the thread loop around said container, and a follower resiliently supported and moved by said cam and engageable with said thread loop for guiding the thread loop of said cam. 5

4. In a sewing machine, a bobbin container with a passage for the thread, an annular gear around said container and of a substantial width 10 in relation to the width of said container, rotatively supported pinion gears meshing with said gear and having flanges engaging the sides of said gear and rotatively supporting same, means for driving one of said pinion gears, and 15 top thread loop catching hooks superimposed and on opposite sides of said gear for catching the top thread looped by the needle and guiding said loop between a pair of teeth of said gear and then around said bobbin container. 20

HENRY WEISSMANN.
